(57) **CLAIM**

The ornamental design for a novel molded fire extinguisher cabinet, as shown and described.

DESCRIPTION

FIG. 1 is a front view of the novel molded fire extinguisher cabinet.

FIG. 2 is a rear view of the novel molded fire extinguisher cabinet of FIG. 1.

FIG. 3 is a left side view of the novel molded fire extinguisher cabinet of FIG. 1.

FIG. 4 is a right side view of the novel molded fire extinguisher cabinet of FIG. 1.

FIG. 5 is a top view of the novel molded fire extinguisher cabinet of FIG. 1.

FIG. 6 is a bottom view of the novel molded fire extinguisher cabinet of FIG. 1.

FIG. 7 is an upper front right perspective view of the novel molded fire extinguisher cabinet of FIG. 1.

FIG. 8 is an upper front left perspective view of the novel molded fire extinguisher cabinet of FIG. 1.

FIG. 9 is an upper rear right perspective view of the novel molded fire extinguisher cabinet of FIG. 1.

FIG. 10 is an upper rear left perspective view of the novel molded fire extinguisher cabinet of FIG. 1.

FIG. 11 is a front view of the novel molded fire extinguisher cabinet of FIG. 1 with door opened.

FIG. 12 is a left side view of the novel molded fire extinguisher cabinet of FIG. 11 with door opened.

FIG. 13 is a right side view of the novel molded fire extinguisher cabinet of FIG. 11 with door opened.

FIG. 14 is a top view of the novel molded fire extinguisher cabinet of FIG. 11 with door opened.

FIG. 15 is a bottom view of the novel molded fire extinguisher cabinet of FIG. 11 with door opened.

FIG. 16 is an upper front right perspective view of the novel molded fire extinguisher cabinet of FIG. 11 with door opened.

FIG. 17 is an upper front left perspective view of the novel molded fire extinguisher cabinet of FIG. 11 with door opened.

FIG. 18 is an upper rear right perspective view of the novel molded fire extinguisher cabinet of FIG. 11 with door opened; and,

FIG. 19 is an upper rear left perspective view of the novel molded fire extinguisher cabinet of FIG. 11 with door opened. The broken lines showing a lock are for illustrative purposes and form no part of the claimed design.
